UNITED STATES PATENT OFFICE

2,535,094

CONTINUOUS FLOW MULTIPLE TANK FUEL SYSTEM

David Samiran, Fort Wayne, Ind.

Original application August 1, 1945, Serial No. 608,348, now Patent No. 2,516,150, dated July 25, 1950. Divided and this application December 23, 1949, Serial No. 134,795

3 Claims. (Cl. 177—311)

(Granted under the act of March 3, 1833, as amended April 30, 1928; 370 O. G. 757)

1

The invention described herein may be manufactured and used by or for the United States Government for governmental purposes without payment to me of any royalty thereon.

This invention is a division of my copending application Serial No. 608,348, filed August 1, 1945, which on July 25, 1950, was issued as Patent No. 2,516,150, and relates to aircraft fuel systems.

In modern aircraft, particularly in warcraft, it is current practice to carry the fuel in a series of separate tanks distributed as uniformly as practicable throughout the available space in the craft, this practice being conducive to uniform weight distribution as well as having the advantage that if one tank is punctured and loses its fuel, the loss will be proportionally less as the number of tanks is greater.

In multiple tank fuel systems as heretofore constructed and arranged, a selector cock has usually been provided with a position for each tank whereby the pilot upon noting that one tank is empty switches the selector to another. This arrangement, however, has the disadvantage that an emergency pump is required which will pump fuel from some assured source while the change-over from one tank to another is being effected, together with a pressure drop sensitive instrument which will start and stop the emergency pump as the pressure situation requires.

One of the objects of the present invention is to provide a multiple tank fuel system in which, by a single setting of a selector cock, the entire contents of a series of fuel tanks will be delivered to the carburetor of an aircraft engine without the slightest interruption in the flow, but still retaining the ability, when conditions warrant, to manually select the tanks one after the other in any order which the circumstances may indicate as desirable.

In long range missions, particularly in long range bombing missions, where maneuverability is not a requirement during flight to the objective but usually becomes highly important upon arrival at the objective, it is current practice to provide a series of externally borne drop tanks, the fuel in which preferably is used first in getting to the objective, whereupon the drop tanks are discarded.

It is therefore another object of this invention to provide a series of drop tanks which may preferably include a right-wing tank, a left-wing tank, and a belly tank, with means whereby the wing tanks will be emptied uniformly, part out of each tank, so as to maintain a balanced condition,

2

the wing tanks being completely emptied before any fuel is withdrawn from the belly tank.

Another object is to provide suitable signal means to indicate to a pilot when fuel in a tank is getting low, together with means to shut off the signal together with the pump when the said tank is completely empty.

Other objects, advantages, and meritorious features will become apparent as the invention is further described with reference to the drawings, wherein:

Fig. 1 is a schematic layout of the improved fuel system which is the subject of this invention.

Fig. 2 is an axial section through one of the float-operated valves shown in the closed position and used to prevent more fuel entering a tank after it is filled to a predetermined level.

Fig. 2a is a fragmentary section showing the valve of Fig. 2 open.

Fig. 3 is a vertical section through the air pressure control valve when closed.

Fig. 3a is a fragmentary section through the valve of Fig. 3 in the open position.

Fig. 4 is a longitudinal vertical section through one of the float-operated valves used in the drop tanks to maintain their fuel in a level condition.

Like reference characters refer to like parts throughout the several views.

Referring now to the drawing, an aircraft engine 10 carries the usual engine pump 12 which is operatively connected to the engine to be driven thereby and adapted to supply fuel under pressure to the carburetor 14 or to a like fuel metering device. A main tank 16 is carried within the aircraft as a permanent part thereof, while a right wing tank 20, a left wing tank 22 and a belly tank 24 are carried externally with releasable connections, 26 and 27, for discarding them when they have served their purpose. A selector cock 28 has its common outlet connected by a pipe 28 to the suction side of the engine pump 12.

Pipes 30 and 34 carry the fuel from the main and drop tanks, respectively, to the several inflow openings of the selector. The handle 36 of the selector has a pointer 38 for indicating when the selector is set at a desired position. Indicia "M" and "D" on the face of the selector facilitate the setting for taking fuel from the main and drop tanks, respectively. The pointer may be moved to third or "Off" position which indicates that all inlets to the selector are closed.

An electrically driven main pump 40 is provided for taking fuel from the main tank 16, the fuel being delivered through the pipe 30 to the position "M" on the selector 28, and, when the

selector pointer is at "M" through the pipe 28 to the carburetor 14. Suitable electric connections are made from the selector position "M" to the main pump 40.

In order to cause the drop tanks 20, 22, and 24 to discharge fuel through the pipe 34 to position "D" on the selector, these tanks are pressurized, the pressure employed being sufficiently high to raise the fuel by way of a branch pipe 44 to the top of, and into the main tank 16, when so desired. A check valve 45 is provided to prevent return flow in pipe 44. A check valve 45 is spring loaded whereby, with a uniform pressure in the branches 54, 56 and 58, the fuel in the wing tanks 20 and 22 will be transferred to the main tank 16 ahead of the fuel in the belly tank 24. A combined float operated valve-and-switch mechanism 65 is placed in the bottom of each of the drop tanks 20, 22 and 24, the valves being provided to insure that the fuel will move out of each tank through the fuel pipes 44 and 61 uniformly, thereby to maintain a balanced condition, and the switches being provided to light a signal light when the drop tanks are nearly empty. A manual switch not shown is provided and used when it is desired to make the switches of the float mechanism ineffective. The combined float operated valve and switch mechanism identified by the numeral 65 in Fig. 1 is shown to a larger scale and in greater detail in Fig. 4 and will be hereinafter more fully described with reference thereto.

As a means for providing the necessary pressure for the drop tanks, the vacuum pump 46 is used. This pump is already part of the standard equipment on aircraft where vacuum operated instruments are employed. The discharge or pressure side of the vacuum pump 46 is connected through pipe 47, air-oil separator 48, pipe 49, check valve 50, and an air pressure control valve 51, to the air pressure line 52 from which branches 54, 56, and 58 extend to the tops of the drop tanks 20, 22 and 24 respectively. The check valve 50 is biased to prevent return flow to the pump 46. An air pressure control pipe 59 connects the vacuum side of the pump 46 to the air pressure control valve 51. The air pressure control valve, identified in Fig. 1 by the numeral 51, is shown in greater detail and to a larger scale in Figs. 3 and 3a, and is hereinafter described with reference thereto.

The drop tank fuel transfer pipe 44 discharges into the top of the main tank 16 through float valve 66 this float valve being designed to prevent any more fuel entering tank 16 after a predetermined level is reached. The float valve identified in Fig. 1 by the numeral 66 is shown to a larger scale and in greater detail in Figs. 2 and 2a and will be hereinafter described with reference thereto.

The float valve, identified in Fig. 1 by the numeral 66, and shown in detail in Figs. 2 and 2a, comprises a housing in two parts, 180 and 182, with a diaphragm 184 clamped therebetween. The upper part 180 has a flange 196 secured thereto to facilitate connection to the upper side of the tank 16. A hose connection 188 is secured to the upper part 180 by a clamp ring 110 which is secured to the upper housing part 180 by screws 112.

The upper housing part 180 has a central hub 114 with an opening 116 which is in alignment with the opening in the hose connection 188 and connected pressure tight thereto. An annular space 118 surrounds the hub 114 and has a series of radial openings 120 connecting the annular space to the outside of the housing. A valve

washer 122 carried on the upper side of the diaphragm 184 is secured thereto by a cup-shaped member 124 having a small central leakage opening 126. A spring 128 has its lower end seated on a portion of the lower housing part 182 and its upper end seated in the cup-shaped member 124, whereby the valve washer 122 is maintained on the seat formed by the end of the hub 114.

A chamber 130 formed immediately under the diaphragm 184 is adapted to receive fluid under pressure through the small leakage opening 126 whereby the valve washer 122 is maintained on its seat. A float 132 of cork or similar material has attached to the upper side thereof by bolts 134 a sheet metal member 136 which carries a pair of hinge ears 138 whereby the float may have hinged connection with the housing portion 182 by means of the hinge pin 140.

A small valve 142 has a groove 143 around its lower end adapted for engagement with the sheet metal member 136, whereby the valve 142 is maintained in closed position as long as the float is in its upper position shown, whereby the chamber 130 builds up pressure through the opening 126, and, being sealed against leakage through the valve 142 therefore maintains the valve washer 122 in its closed position as shown. When, however, by reason of fluid being withdrawn from the tank 16 the float 132 drops to a lower position, the small valve 142 will be opened and the chamber 130 thereby drained, whereupon fluid will flow in through the connection 108 past the valve part 122 and its seat, outward through the annular space 118 and radial openings 120 into the tank 16. An adjustable screw stop 144 limits downward travel of the float.

Air pressure control valve, Figs. 3 and 4a, identified in Fig. 1 by the numeral 51, shown in section and to a larger scale, comprises a valve body 180 with a rear head 182 and a front head 184 secured thereto by screws 186, a diaphragm 187 and a gasket 188 being clamped under the rear head 182 and front head 184, respectively, by screws 186 thereby making a pressure tight joint between the body and the two heads and dividing the interior of the valve body into three compartments 208, 209, and 216. Hose connections 190 and 192 are provided for connecting to the pipes 49 and 52, respectively. A valve head 194 is secured by a small bolt 196 to the diaphragm 187. A spring 198 has the front end acting against the diaphragm 187, the rear end reacting against an internally threaded part 200 which is adjustable axially by a screw 202. A cap 204 clamps a washer 206 in position, washer 206 being provided as a bearing for the adjusting screw 202. The chamber 208 above the valve head 194 is connected by a passageway 210 to the atmosphere. The chamber 209 is connected to the pressure side of the pump 46 and to the tops of the drop tanks 20, 22 and 24. The valve seat 212 in the body 180 has a series of openings 213 which are uncovered when the valve head 194 rises from its seat as in Fig. 3a. A pipe connection 214 adapted for connection to the pipe 59, Fig. 1, connects the vacuum side of the pump 46 to the chamber 216 for influencing the action of the diaphragm 187. When the valve 194 is closed, as it necessarily is during normal operation, the leftward force in the chamber 209 greatly exceeds the rightward force in that chamber, because, in chamber 209, there is a greater left wall area than right wall area exposed to the same psi pressure. Moreover, the leftward force contributed by the vacuum in chamber 216 must be added to the leftward force

accruing from chamber 209. The spring 198 is then proportioned and adjusted so that it exerts a rightward force somewhat less than that necessary to open the valve 194 as long as the pressure in chamber 209 is normal, but, should a leak occur in pipe connection 190 or 192, so that the pressure in chamber 209 would drop below the required value, the spring 198 would open the valve 194 thereby instantly connecting the tops of all drop tanks to the atmosphere through the connection 210, a condition necessary if the fuel is to be pumped out of the drop tanks instead of being forced out by pressure. An advantage of this construction is that if the vacuum pump 46 should cease to function, the valve 51 will open and the space in the drop tanks above the fuel level will be connected to the atmosphere by way of the opening 210 and the selector cock may then be set to allow the engine pump 12 to draw the fuel directly from the drop tanks.

The float-controlled valve and switch mechanisms, identified in Fig. 1 by the numeral 65 and shown in section and to a larger scale in Fig. 4, are provided with flanges 218 by which they are joined to openings in the bottoms of the drop tanks 20, 22 and 24 by bolts not shown. Each valve and switch mechanism has a body 220 having a valve housing 222 secured to upwardly extending posts 221 on its upper side by screws 223, screen covers 225 and 227 being provided through which fuel from the drop tanks must flow to pass through the valve and a switch housing 224 secured to its lower side by screws which do not appear in the view shown.

The midportion of the body 220 contains the mechanism which provides the necessary interaction between the valve and the switch. The valve housing 222 has a pair of spaced apart ears 226 between which a float-operated lever 228 is hinged by the pin 230. A tubular arm 232 has one end anchored in the lever 228 while its outer end carries a float 234. The lower end of the lever 228 is extended laterally at 236 to provide means for operating the valve to opened or closed position as the float rises or falls. A resilient valve disc 238 dies in a saucer-like part 240 and is held in the desired position by a pin 242 which passes through openings in the disc and through an opening in the lever extension 236 near its outer end.

A wire washer 244 between the part 240 and 236 and a cotter pin 246 positioned slightly away from the bottom of the extension 236 permits limited rocking movement of the valve disc 238 whereby it may effectively engage the seat 248 in the valve housing 222 when the float is in its lower position. A switch-operated trigger 250 is secured to the lever 228 by a screw 252, the trigger having an elongated slot 254 whereby it may be adjusted horizontally.

A neck 256 is made integral with the valve housing 222 for receiving the lower ends of the pipes 44, 61 and 67, Fig. 1, these lower ends being fixed in and made a part of the drop tanks. Washers 258 of soft synthetic rubber or similar material alternating with washers 260 of harder material are held in the neck 256 by a snap ring 262. An entire unit 65 may thus be assembled into a drop tank by merely pushing it up from the bottom so that a pipe enters a neck 256, then bolting the flange 218 to the tank.

The switch operating mechanism, whereby an electric light is lit when the drop tank is nearly empty and extinguished when it is quite empty

comprises a flanged hub member 264 with a diaphragm 266 and a diaphragm clamp ring 268 all clamped together and fastened to the body 220 by the screws 270, a gasket 272 being provided between the member 264 and the body 220 to seal against leakage from the valve compartment into the switch compartment.

A central opening in the member 264 is tapered in both directions from the middle as at 274 to freely receive the rockable switch actuating lever 276 which is hinged in the opening by the pin 278. The switch-actuating lever 276 includes a stem 280 which extends upwardly from the body of the lever leaving a shoulder upon which the collar 282 rests, a gasket 284 being placed under the collar to prevent leakage. A spring 286 forces a collar 288, the diaphragm 266, the collar 282 and the gasket 284 together and against the shoulder on the body of the lever 276 whereby leakage along the stem 280 is prevented. The reaction of the upper end of the spring 286 is taken by the nut 290 which is adjustable on the upper threaded end of the stem 280. A jam nut 292 locks the nut 290 in the adjusted position, the upper end 294 of the jam nut 292 is of conical form and engages the depending end of the trigger 250. A switch operating arm 296 depends from the body of the lever 276 and is adapted to engage the operating stem 298 of a switch 300.

Switch 300 is of conventional form being of the type which makes electrical contact when the stem 298 is pushed in, and breaks contact when the stem is released. The switch is mounted on an insulating plate 302 which is adjustable horizontally by loosening the screws 304 so that the arm 296 substantially touches the stem 298 when in the closed valve position shown.

A frusto conical spring 305 rests upon a shoulder in the member 264, its upper end bearing against the collar 282 to maintain the actuating lever 276 in the neutral position shown.

Binding posts 306 are connected one to a source of electrical energy and the other grounded to the housing 224 by flexible leads 310, a light 312 or other signal being inserted in the circuit.

The operation of the system is as follows:

Assuming all tanks to be filled, the pilot may preferably turn the selector to "M" and start the engine 16, the fuel pump 40, and the vacuum pump 46.

Since the tops of the drop tanks 20, 22 and 24 are all connected through conduits 52, 54, 56, 58, 61, 60, 49, 47 to the pressure side of the vacuum pump 46, the fuel in the drop tanks is pressurized, the pressure being sufficient to cause the fuel to flow through the conduits 67, 61 and 44 to the top of the main tank 16 through the float valve 66 and into the tank from which it is pumped by the electrically driven pump 40 to the suction side of the engine pump 12, the float valve 66 admitting pressurized fuel from the drop tanks 20, 22 and 24 only so fast as the pump 40 removes fuel from the main tank 16 and delivers it to the suction side of the engine pump 12.

If the main tank 16 should be damaged, or the electrically driven pump 40 should fail to function, the selector may be turned to "D," whereupon the pressurized fuel in the drop tanks will be delivered through conduits 67, 61, 44, 34, and 28 directly to the suction side of the engine pump 12. It is the function of the spring-loaded valve 45 to retain the fuel in the belly tank 24 until after the wing tanks are emptied, and it is the function of the float valve 65 in the two wing tanks 20 and 22 to restrict the fuel outlet most

in the tank in which the fuel is lowest, thereby to cause the two wing tanks to maintain a balanced relation.

When the two wing tanks are nearly empty, the switch operating triggers 250 of the float valve-and-switch mechanism 65, Fig. 4, contact the cone 294 on the left side and lean the switch actuating lever 276 progressively more to the right as the tank becomes more nearly empty, thus closing the switch 300 of the float mechanism 65 while there is still a small quantity of fuel in the tank and thereby lighting the signal light 306, Fig. 1, indicating to the pilot that the fuel in the wing tanks is almost depleted. The trigger 250 and the cone 294 are so adjusted, with respect to the float 234, that just as the tank becomes quite empty, the trigger 250 passes over center on the cone 294 to the right side of center (see Fig. 4) and the switch 303 is thereby opened and the signal 312 thereby extinguished, just as the valve disc 238 is pressed onto the seat to its closed position. At the option of the pilot the two wing tanks 26 and 22 may now be dropped by undoing the connections 25, 27. The mechanism by which the pilot may loosen these connections to drop these tanks forms no part of this invention and is therefore not herein shown.

After the wing tanks are thus emptied and dropped, fuel flows from the belly tank 24 until its float operated valve-switch mechanism 65 lights the warning signal 76 to indicate that the tank is nearly empty, then shuts off the signal and closes the valve when the tank is quite empty. The belly tank 24 may now also be dropped.

Having described my invention, I claim:

1. In a continuous flow fuel system for an aircraft, a main tank, a drop tank, a fuel outlet control means at the outlet of the drop tank through which the fuel flows from the drop tank to the main tank, a signal associated with said control means, means in the drop tank operative at a predetermined low level of the fuel in the

drop tank to operate said signal, and means operative upon an empty tank condition in said drop tank to discontinue said signal and close said fuel outlet control means.

- 5 2. In a fuel system for an aircraft, a drop tank having an outflow passageway, an electric signal adapted to close said passageway and light said signal, a combined valve and switch mechanism, a float operative at a predetermined low level of 10 the fuel in said tank to close said switch mechanism to operate said signal, and at a lower predetermined level of said fuel to open said switch to discontinue said signal and coincidentally to close said valve.
- 15 3. In an aircraft fuel system, a tank having a fuel discharge opening, an electric signal, an electric switch electrically connected to said signal for controlling said signal, a valve in said discharge opening operable to open or closed position 20 for controlling discharge from said fuel discharge opening, a float supported in said tank for operating said valve and said switch to open or closed positions, a switch closing part on said switch, a float operated part on said valve operable into engagement with said switch closing part by movement of said float to a predetermined low level, whereby said switch is operated and said signal is lit, and operable further and into disengagement from said switch closing part 25 to allow said switch to open and disconnect said signal upon movement of said float to the valve closing position.

DAVID SAMIRAN.
